(57) **CLAIM**

We claim the ornamental design for an induction range, as shown and described.

DESCRIPTION

FIG. 1 is a front perspective view of a first embodiment of an induction range showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 4;

FIG. 9 is a front perspective view of the induction range in a state of use;

FIG. 10 is an exploded view thereof showing the induction range in a state of use;

FIG. 11 is a front perspective view of a second embodiment of the induction range showing our new design;

FIG. 12 is a front view thereof;

FIG. 13 is a rear view thereof;

FIG. 14 is a left-side view thereof;

FIG. 15 is a right-side view thereof;

FIG. 16 is a top view thereof;

FIG. 17 is a bottom view thereof; and,

FIG. 18 is an enlarged view of the encircled portion in FIG. 14.

(Continued)

The evenly-dashed broken lines in the figures depict portions of the induction range that form no part of the claimed design.

The dot-dashed broken lines encircling portions of the claimed design that are shown in enlargements form no part of the claimed design.
